UNITED STATES PATENT OFFICE.

WILLIAM LEONARD AND WILLIAM E. LEONARD, OF CHELSEA, MASSACHUSETTS.

IMPROVEMENT IN HARNESS-SADDLES.

Specification forming part of Letters Patent No. 118,137, dated August 15, 1871.

To all whom it may concern:

Be it known that we, WILLIAM LEONARD and WILLIAM E. LEONARD, both of Chelsea, in the county of Suffolk and State of Massachusetts, have invented a new and useful Improvement in Harness-Saddles, of which the following is a specification:

Our invention consists in so arranging and combining a back-strap holding metal piece with a stiffening-plate that, by means of the turret at the upper end and a rivet on the lower end of the back-strap piece, all the parts are held together without any other additional fastening.

In the drawing, Figure 1 is a side elevation of our improvement, the turret and jockey being removed from its bearing and thrown upward. Fig. 2 is a similar view of the back of the same; and Fig. 3 is a section in line *x x*, Fig. 1.

Like letters of reference indicate like parts in the several figures.

A in the drawing represents the usual iron saddle proper, provided with wings A', which have longitudinal inward depressions for the stiffening to rest in. B is one of the saddle-flaps, secured to its wing A' by means of rivets or clinched nails *a*. At its upper end this strap B is provided with two cuts, so that a central portion, *b*, thus formed may lie on the metal stiffening-plate C and be in the recess thus formed a protection against the rubbing of the stiffening-plate C against the upper end *d* of the metal piece D, which also fits into that recess. This end *d* is provided with an elongated square slot, into which fits a similarly-shaped leather nut, *e*, through which the screw end of the turret E passes. The wing A' has in its recess a slot to correspond with the slot of end *d* of piece D, and through which and a suitable opening in the stiff-

ening-plate the shank *f* of a screw-nut, F, passes, which latter serves for a bearing into which to screw the lower end of turret E, and thus hold all the pieces firmly together. G is a jockey secured to the saddle proper, through which turret E passes, and which covers and hides the upper portion of a saddle-strap, B, and the parts below where they are secured together. On the inner side, at the lower end of metal piece D, is formed a rivet, *d'*, which passes through strap B and stiffening-plate C, on which latter it is riveted. In this manner the stiffening-plate C serves also to hold the lower end of piece D with the loop *g*, to which the back-strap H is fastened, while the turret holds all the parts together at the upper end.

By means of our improvement a harness-saddle is produced much less bulky than where the usual leather stiffening is used, and having a finer appearance, while, at the same time, the back-strap is held much more securely than formerly.

What we claim as new, and desire to secure by Letters Patent, is—

The back-strap holding-piece D, with its slotted upper portion *d* and rivet *d'* at its lower portion, and the stiffening-plate C, when arranged as described and shown, to hold all the parts together by means of the turret E and screw-nut F at the upper and by means of rivet *d'* at the lower end, without other fastening, substantially as described.

WILLIAM LEONARD.
WILLIAM E. LEONARD.
